COMBINED ELECTRIC SWITCH AND
RESERVE FUSE MOUNTING

Anthony Kreek, McKeesport, Pa.

Application April 19, 1935, Serial No. 17,315

2 Claims. (Cl. 200—125)

This invention relates to certain new and useful improvements in combined electric switch and reserve fuse mounting.

The primary object of the invention is to provide a combined electric switch and reserve fuse mounting wherein an enclosed switch box houses fuses arranged in any multiple desired, four of such fuses being illustrated with two of the fuses active and two held in reserve to be placed in the circuit should either one of the previous active fuses become damaged or burned out.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a top plan view of a combined electric switch and reserve fuse mounting in an enclosing casing with the cover of the casing in open position;

Figure 2 is a fragmentary end elevational view showing the position of the hand operated lever for the movably mounted fuses in one position with two of the four fuses in the circuit;

Figure 3 is a similar fragmentary end elevational view showing the hand lever in a reverse position with the other two of the four fuses in the circuit;

Figure 4 is a fragmentary end elevational view showing the hand lever in position with all fuses out of the circuit with the cover of the casing released for opening movement;

Figure 5 is a fragmentary plan view showing the manually operated cut-out of the circuit locked in its cut-out position;

Figure 6 is an end elevational view of the enclosing casing showing the lead-in wires and a clamp device engaged with one of the wires to aid in the support of the casing;

Figure 7 is a vertical cross-sectional view taken on line 7—7 of Figure 4, showing the operating means for shifting the fuses for selectively positioning a pair of the four fuses in the circuit;

Figure 8 is a cross-sectional view taken on line 8—8 of Figure 7;

Figure 9 is a fragmentary side elevational view, partly in section showing the lock device for the casing cover;

Figure 10 is a diagrammatic view showing the contact for the first and third fuses in engagement;

55 Figure 11 is a diagrammatic view showing the

contact for second and fourth fuses in engagement;

Figure 12 is a diagrammatic view of another arrangement of contacts in which the contacts for first and second fuses are in engagement; and 5

Figure 13 is a fragmentary perspective view of a part of the safety switch.

The combined electric switch and reserve fuse mounting comprises a casing having a bottom wall 15, side walls 16 and 17, end walls 18 and 19 10 and a cover wall 20 hinged as at 21 to the free edge of the side wall 17 with a lock device associated with the free swinging edge of the cover wall 20 and the free edge of the side wall 16.

The casing is preferably of rectangular construction and houses a rectangular insulation plate 22 that is spaced from the bottom wall 15 by depending end legs 23, the plate being anchored to the bottom wall by means of bolts 24 or the like. The plate 22 carries a series of contacts 15 20 on its upper face as shown in Figures 1, 7, 10 and 11, the contacts comprising pairs of transversely aligned contact strips 25—26 and 27—28. The contact strips 25 and 26 carry lateral projections 29 extending in the same direction with 25 an upstanding U-shaped contact 30 at the end of each extension 29. Extensions 31 project in the same direction from the inner ends of the contact strips 25 and 26 and laterally thereof with upstanding U-shaped contacts 32 at their outer 30 ends. Lateral extensions 33 project from the inner ends of the contact strips 27 and 28 in the same directions as the extensions 29 on the contact strips 25 and 26 and each extension 33 carries an upstanding U-shaped contact 34 aligned with 35 the contacts 30. Extensions 35 project laterally of the contact strips 27 and 28 intermediate their ends and in the same direction as the extensions 31 on the contact strips 25 and 26 and each extension 35 carries at its outer end an upstanding U- 40 shaped contact 36 that aligns with the contacts 32. Electrical conductors 37 from a source of energy enter the casing through openings in the top wall 18 and are connected to the contact strips 25 and 26 respectively, the outlet conductors 38 45 extending from the contact strips 27 and 28 through openings 19 in the bottom wall of the casing. As shown in Figure 6, a clamp device 39 hinged to the top wall 18 of the casing is adapted to be moved into binding engagement with one 50 of the conductors 37.

A safety switch is associated with the contact strip 26 and has a lock device attached thereto when the safety switch is in open position, to break the flow of current through the switch box 55

and to eliminate the danger of injury to an operator or repair man. As shown in Figures 1, 5 and 13, a switch plate 40 is pivotally supported on the insulation member 26a set into the interrupted 5 contact strip 26 and when positioned as shown in Figure 1 is closed with current flowing through the contact strip. When it is desired to break the flow of current, the switch plate 40 is moved on its pivotal support and assumes the position 10 shown in Figure 5. With the switch plate 40 so disposed, the same is restrained from pivotal movement by means of the leg 42 of a bell crank lever that carries at its free end an abutment block 42a shown in detail in Figure 13 with one face of 15 the abutment block grooved as at 42b for engagement with the pin 41 rising from the switch plate 40. As shown more clearly in Figure 13, the other leg 42c of the bell crank lever carrying the abutment block 42a is adapted to be aligned with an 20 arm 40a rising from the plate 22 and said arm and leg 42c have registering openings 42d for the passage of a shackle of a lock 41a shown in Figure 5. It will therefore be seen that the switch plate 40 is locked in its circuit breaking position 25 against accidental movement to closing position and with injury to the operator or repair man eliminated.

A ledge 43 rises from each side edge of the plate 22 above the support 23 and an insulation carrier 30 plate 44 is slidably mounted on the ledges 43. As shown in Figures 1, 7 and 8, angle iron strips 45 are interposed between the upper and outer sides of the ledges 43 and the carrier plate 44 with the carrier plate secured to the angle iron strips 45 35 by means of fastening devices 46. The angle iron strips 45 have a pin and slot connection 47 with the ledges 43 to be limited and guided in their movements.

As shown in Figure 1, four fuses 48, 49, 50 and 40 51 are carried by the upperside of the carrier plate 44 with the blades 52 of the fuses engaged with U-shaped contacts 55 on the upper side of the carrier plate 44, the contacts 55 communicating with blade contacts depending from the carrier 45 plate 44, the blade contacts associated with the contact strips 25 and 26 being designated by the reference characters 56, 57, 58 and 59, while the blade contacts associated with the contact strips 27, and 28 are designated by the reference characters 60, 61, 62 and 63 as diagrammatically illustrated in Figure 10.

The carrier plate 44 is adapted to be shifted within the casing for placing the pairs of fuses 48—50 and 49—51 into the electrical circuit and 55 to accomplish the sliding movement of the carrier plate 44, with the fuses thereon and the contact blades, there is provided a cross shaft 64 shown in Figure 7 as being journaled in the plate supports 23 and also in bearings 65 depending 60 from the plate 22, the opposite ends of the shaft 64 being keyed as at 66 and having an arm 67 fixed to each key portion with a link 68 at the upper end of the arm that is pivotally connected at its outer end as at 69 to the angle iron strip 45 65 as shown in Figure 1. One keyed end of the shaft 64 extends through the side wall 16 of the casing and carries an operating handle 70.

A lock device is associated with the casing and cover for holding the cover in locked position 70 when either pair of fuses is in the circuit and as shown more clearly in Figures 7 and 9, an arm 71 is fixed to the adjacent keyed portion 66 of the shaft 64 and the free end thereof is socketed for the reception of a pin 72 that is spring pressed 75 as at 73 to be projected from the upper end of

the arm 71 for reception in the recesses 74 in the curved edge 75 of the plate 76 for holding the shaft 64 and carrier plate 44 in its shifted position. A pin 77 projects laterally from the upper free end of the arm 71 and works in a slot 78 in the side wall 16 of the casing and has its free end receivable in the opening 79 in the plate 80 that is secured to the inner face of the side wall 16 and which plate is spring pressed toward the side wall as at 81. An abutment lug 82 is carried 10 by the free swinging edge of the casing cover 20 and when the cover is in closed position on the casing, the abutment lug 82 moves into engagement with the apertured plate 80 to move the same away from the side wall 16 and to displace 15 the opening 79 relative to the pin 77. When either pair of fuses is in the circuit, the cover 16 is locked in closed position on the casing by means of the latch 83 that is pivoted as at 84 on the side wall 16 of the casing, the lower end of 20 the latch 83 being slotted as at 85 with the pin 77 extending therethrough, the latch 83 being selectively engageable at its upper end with the keeper hooks 86 carried by the cover 20. The latch 83 is moved on its pivot 84 when the arm 25 71 is shifted upon rotation of the shaft 64.

When the cover 20 is closed on the casing, the apertured plate 80 is spaced from the pin 77 and when the handle 70 is positioned as shown in Figure 4, the latch rod 83 is disengaged from the keeper hook 86 and the cover 20 can be readily opened on its hinged connection with the casing for access to the casing. With the parts so disposed, the blade contacts are spaced from the contacts 30 and 34 and at this time, the circuit 35 may be broken by moving the switch 40 from the position shown in Figure 1 to the position shown in Figure 5 with the switch 40 locked in its open position by the device 42. The contacts depending from the carrier plate 44 and rising from the 40 plate 22 are so relatively positioned as to place either pair of fuses as 48—50 or 49—51 in the circuit. Should one of the fuses of a pair burn out, the handle 70 may be thrown to either of the positions shown in Figures 2 and 3, and a 45 new pair of fuses placed in the circuit. The movements of blade contacts relative to the contact strips are illustrated in Figures 10 and 11.

The contact strips and contact blades associated therewith may be so arranged as to cause 50 the pair of fuses 48—49 and 50—51 to be selectively placed in the circuit as disclosed in Figure 12, the contact blades 52a of the fuses 48 and 49 being positioned for engagement with the contacts 30a and 34a while the contact blades 52b 55 of the fuses 50 and 51 are out of engagement with the contacts 32a and 36a.

From the above detailed description of the invention, it is believed that the construction and operation thereof will at once be apparent and 60 while there are herein shown and described the preferred embodiments of the invention, it is nevertheless to be understood that minor changes may be made therein without departing from the spirit and scope of the invention as claimed. 65

I claim:

1. In a combined electric switch and reserve fuse mounting, a casing and hinged cover therefor, a fixed plate mounted in the casing in spaced relation to the bottom wall thereof, fixed contacts rising from the upper face of the plate, four fuses movably mounted in the casing, a pair of contacts movable with each fuse and arranged with respect to the fixed contacts whereby a pair of the movable contacts is selectively engageable 75

- with two of the fixed contacts, means operable exteriorly of the casing for moving the fuses, electric circuit wires in communication with the fixed contacts, the mounting for the fuses and movable contacts including a plate slidably supported at its opposite edges on the fixed plate and in spaced relation thereto, the movable contacts depending from the slidable plate, a journalled shaft extending across the casing beneath the fixed plate, and an upwardly extending arm and link connection between the ends of the shaft and the sliding plate.
2. In a combined electric switch and reserve fuse mounting, a casing and hinged cover therefor, a fixed plate mounted in the casing in spaced relation to the bottom wall thereof, fixed contacts rising from the upper face of the plate, four fuses movably mounted in the casing, a pair of contacts movable with each fuse and arranged with respect to the fixed contacts whereby a pair of the movable contacts is selectively engageable
- with two of the fixed contacts, means operable exteriorly of the casing for moving the fuses, electric circuit wires in communication with the fixed contacts, the mounting for the fuses and movable contacts including a slidable plate, ledges rising from opposite sides of the fixed plate, angle iron wear strips depending from opposite edges of the slidable plate and slidably supported on the ledges, pin and slot connections between the angle iron strips and ledges to limit movements of the sliding plate, a journalled shaft extending across the casing beneath the fixed plate, an arm fixed to each end of the shaft and rising therefrom, horizontal link connections between the upper ends of the arms and corresponding ends of the adjacent side portions of the angle iron strip for effecting sliding movements of the sliding plate and coaction of the contacts.

ANTHONY KRCEK. 20
